Primary Examiner — Cynthia Ramirez*Assistant Examiner* — Jeremy S. Swartz(74) Attorney, Agent, or Firm — Michael A. Catania(57) CLAIM

The ornamental design for a towel attachment device, as shown and described.

DESCRIPTION

FIG. 1 is a side perspective view of the towel attachment device showing our new design;

FIG. 2 is a front plan view thereof;

FIG. 3 is a left side plan view thereof;

FIG. 4 is a top plan view thereof; and,

FIG. 5 is a bottom plan thereof.

The broken lines in the drawings illustrate portions of the towel attachment device and form no part of the claimed design.

1 Claim, 4 Drawing Sheets(56)
